UNITED STATES PATENT OFFICE.

THEOPHILUS BROWN, OF MOLINE, ILLINOIS, ASSIGNOR TO MARSEILLES COMPANY, OF EAST MOLINE, ILLINOIS, A CORPORATION OF ILLINOIS.

MANURE-SPREADER.

1,139,483.

Specification of Letters Patent. Patented May 18, 1915.

Application filed February 1, 1912. Serial No. 674,675.

To all whom it may concern:

Be it known that I, THEOPHILUS BROWN, a citizen of the United States, residing at Moline, in the county of Rock Island and 5 State of Illinois, have invented certain new and useful Improvements in Manure-Spreaders, of which the following is a specification, reference being had therein to the accompanying drawing.

10 This invention relates to improvements in manure spreaders of the class in which each is constructed with an elongated load carrying body part, front wheels or truck, feeding mechanism in the lower part of the 15 body, and, at the rear end of the latter, a beater or distributor structure.

The improvements are in the means for mounting and adjusting the beater or distributor and mounting and adjusting the 20 load support and feeding mechanism, and in other matters that will be fully understood from the description below.

Figure 1 is a side view of a mechanism embodying my improvements. Fig. 2 is a 25 partial elevation of the side of the machine opposite to that shown in Fig. 1. Fig. 3 is a partial vertical longitudinal section on a plane at the central part, transversely, of the beater. Fig. 4 is an end view of one of 30 the supporting brackets at the rear end of the feeding mechanism. Fig. 5 is a side view of the same. Fig. 6 is a view partly in rear elevation and partly in section looking at the rear of the machine. Fig. 7 is a 35 view of the planetary gear detached. Fig. 8 shows backing ratchet and pawl mechanism. Fig. 9 is a side elevation of the frame of the feeding apron. Fig. 10 is a view partly in elevation and partly in section of 40 parts at the rear end of the machine. Fig. 11 is a view partly in plan view and partly in section, showing a portion of the feeding apron, the rear axle and connecting devices. Fig. 12 is a view of the bracket which 45 supports the beater upon the axle and also carries the rear end of the feeding apron. Fig. 13 is a plan view of the bracket shown in Fig. 12.

The body part of the machine, which is 50 primarily loaded with the material to be distributed, is formed with a main frame and vertical side walls. 1 indicates longitudinal sills at the bottom of this body part which, at their rear ends, are supported upon the rear axle 2, and at their front ends

upon the front truck having the wheels 3, the upper cross connecting bar 4 and the vertical post or bracket at 5. The side-boards 6 are secured to the sills and cross connecting parts of the frame. These, together with the front wall 7 and the supporting apron at the bottom inclose the space within which the load is retained. The connecting part of the frame, joining the front truck to the body frame, is formed 65 of upwardly curved bars 8.

On the ends of the axle 2 are pivoted the ground wheels, there being backing ratchet devices at 10 interposed between the axle and the wheels.

70 The apron which supports and feeds the material backward is indicated by 15. It is mounted upon a front shaft 18 and the rear shaft 28. It is composed of slats linked together, or to carrying chains 14, and passes around sprockets or spiders at 16 and 17, the former on the rear shaft 28 and the latter on the front shaft 18. These shafts are connected together by means of longitudinally arranged bars 50. 51, 52 are 75 brackets with sleeves that loosely surround the shafts respectively, and to these brackets the rods 50 are secured. From one rod 50 to the other there extend connecting rods 53. Upon these are provided rollers 54, 80 of sufficient number to properly support the apron. The front brackets 52 are shown as having slots 52^a to permit more or less longitudinal movement of the front end of the feeder element of the machine. This 85 is to allow the rear end of the feeder element to move up and down, as will be described.

90 The rear spider shaft 28 is mounted in bearings at 27 carried by two bearing arms 95 25, which are adjustably mounted on the rear axle 2. These arms 25 are part of two bell lever elements indicated by 23, each having an upwardly extending arm 24, in addition to the shorter arm 25, referred to. 100 Each is cast with a sleeve 26, by which it is mounted upon the axle 2.

105 The beater 20 is carried by a shaft 21, which is mounted in bearings, 22, at the upper ends of the arms 24. 29 is a sprocket wheel keyed to the axle 2 near the ground wheel and 30 is a chain driven thereby and in turn driving a sprocket wheel 31 loose on the end of the beater shaft 21. This sprocket pinion 31 110

transmits the rotary motion to the beater through a planetary gear device 32, having the external ring gear or shell gear 33 integral with the sprocket 31 engaging with a series of internal pinions carried by the disk 35, and meshing with the central pinion 34 on the driving sleeve keyed to the beater shaft. On the periphery of the disk 35 there is a series of stop lugs or teeth 36. 5
10 37* is a detent adapted to be brought into and drawn from the path of these stop lugs. When it is out of engagement the disk 35 is free to rotate and at such times the beater shaft will be stationary; but when the detent 15 is in engagement with one of the stop lugs 36 the disk 35 is prevented from rotating and the beater shaft will receive power through the sprocket 31, internal gear 33, the pinions carried by the disk 35 and pinion 34 on the shaft. 20
10 On the other end of the beater shaft there is a sprocket wheel 38, and, in alignment therewith, there is a sprocket wheel 39 concentric with but loose on the axle 2. 40 25 41 is a chain transmitting power from the sprocket 38 to the wheel 39. 41 is a bevel wheel carried by the sprocket 39, and 42 is a bevel pinion engaging therewith. The pinion is on the shaft 44 mounted in the 30 bearings 45, 47, this shaft also carrying the worm 43, which meshes with the worm wheel 48 on the rear apron shaft 28. The sill 1 of the main frame has secured to it a bracket 11, with a sleeve 12, fitted to the axle and the tongue or arm 13 for fastening to the 35 sill. In the plate part of the bracket there is a slot 49 concentric with the axle and the apron shaft 28 extends through this slot and can move up and down therein. 40
10 55 is a link bar or thrust-and-pull rod. At its rear end it is pivotally connected to the bell lever 23 and at its front end is connected to a crank 60, which is secured to shaft 58 mounted on the front part of the 45 frame near the driver's seat. 59 is a ratchet secured to the shaft 58. 61 is a hand lever having a pawl 62 engaging with the teeth of the ratchet. The operator can rock the shaft 58 with a step by step movement when 50 he wishes to throw the crank to its rear position. 63 is a locking dog also engaging with the teeth of the ratchet. It is held in its active position by a foot lever and spring at 64. The manner of operating a spreader 55 having the parts constructed as described will be readily understood. After a load has been discharged and prior to reloading the operator releases the ratchet and permits the crank 60 and the link 55 to move forward, the weight of the feeding mechanism serving to rock the lever 24 forward, bringing with it the beater, the rear end of the feeding apron moving down to its lowermost limit, as shown in Fig. 3. The beater serves as an end gate to retain the load moving for-

ward or rearward in the arcuate slots 21^a cut in the sides of the body. The carrying capacity of the vehicle is largely increased by the dropping of the apron. When the machine reaches the field the load is elevated 70 in the body and should any part thereof extend above the sides there is no material spilling as the distributing mechanism is at work scattering the load.

When, in the field, it is desired to set the distributor to work, the operator by the lever 61 and the intermediate parts actuated thereby, swings the carrier arm 23 backward, this throwing the beater also backward and elevating the rear end of the feeding apron. The detent 37^a is carried by the swinging arm 37 which engages with the lugs or projections on the swinging arm 24, or passes through an aperture therein, and the parts are so related that just at the time the beater reaches its rear position the detent 37 is drawn into the path of the stop lugs 36, and thereupon the power is transmitted from the pinion 31 to the beater shaft and the work of distributing the material commences. The beater having been drawn away from the rear end of the load mass, is free to be put into rapid rotation and get under full inertia before any impedance results from contact with the material. 95

As soon as the beater shaft 21 begins to rotate it, in turn, through the train of parts on the left hand side of the machine, commencing with the sprocket wheel 20 and terminating with the worm wheel 48, imparts power to the feeding apron. The rear end of this apron has been brought up to a proper position in relation to the fingers on the beater and shortly after the beater is set into rotation the load mass has been carried by the apron far enough back for the shredding and distributing to commence. By lifting up the apron the load mass is elevated, as before stated, in the body and this results in freeing it from pressure from the side boards, so that the beater is greatly assisted in shredding it and drawing it backward. 100 105 110

The beater is mounted in the way I have found the most advantageous, namely, by supporting it directly upon the ground wheels through the medium of the axle. The lighter parts of the frame and sides of the body are relieved of all the severe strains and stresses which are exerted by the beater when at work. This advantageous feature I have embodied in distributers of other forms, but believe myself also to be the first to have mounted this element of the mechanism in such a way that it can be moved or adjusted while still remaining supported upon the wheels or axle. 115 120 125

Many of the advantages incident to this mechanism can be attained if the beater is mounted and carried independently of the

feeding mechanism and vice versa, or so that the beater can be moved while the feeder is stationary. But, I prefer to have them related in the way shown and described, that is, so that when the beater moves forward the apron will move downward, and when the beater moves away from the rear end of the load the latter shall be elevated somewhat. The feeding apron can be so mounted, if desired, that it shall rise and fall in horizontal parallelism, instead of having its motion restricted to the rear end.

What I claim is:

1. In a fertilizer distributer, the combination of the body structure, the rapidly rotating beater or distributer, the means for supporting the load in the body, means for feeding the load on horizontal lines toward the beater, and means for elevating the load 20 from one plane to another.

2. In a fertilizer distributer, the combination of the body structure, a rapidly rotating beater, the vertically movable bottom support for the load, and means for feeding the load on horizontal lines toward the beater.

3. In a fertilizer distributer, the combination of the body, the beater, the longitudinally movable bottom support for carrying 30 the load and feeding it to the beater, and means for adjusting the bottom support vertically from one position to another.

4. In a fertilizer distributer, the combination of the body, the beater, and the longitudinally movable bottom support for the 35 load adapted to have its rear end adjusted to either of several positions vertically.

5. In a fertilizer distributer, the combination of the body, the beater, the longitudinally movable bottom support for the load, and means for adjusting the rear end of the bottom support from one position to another vertically.

6. In a fertilizer distributer, the combination of the body, the vertically adjustable load supporting and feeding means, and the longitudinally adjustable beater.

7. In a fertilizer distributer, the combination of the body, the load supporting and 50 feeding means, the beater, and devices for simultaneously adjusting the load supporting means vertically and adjusting the beater longitudinally.

8. In a fertilizer distributer, the combination of the body, the movable bottom for advancing the load, the axle, the ground wheels thereon, the beater mounted on an axis remote from the axle and supported directly thereon, and means for removing 55 the beater to or away from the load about the axle as a center.

9. In a fertilizer distributer, the combination of the body, the axle, the ground wheels mounted thereon, the beater mounted on an axis remote from the axle, and brackets

hinge-connected to the axle and supporting the beater.

10. In a fertilizer distributer, the combination of the body, the axle, the wheels mounted thereon, the beater mounted on an axis remote from the axle, brackets supported by the ground wheels and carrying the beater, and means for swinging said brackets about the axis of the wheels as a center.

11. In a fertilizer distributer, the combination of the body, the movable bottom for advancing the load toward the beater, the ground wheels, the beater carried by the ground wheels and located at a point remote 80 from their axis, and means for moving the beater about the axis of the ground wheels as a center to and away from the load.

12. In a fertilizer distributer, the combination of the body, the movable bottom for 85 advancing the load to the beater, means for moving the beater to and away from the load, and means for lowering or raising the said movable bottom.

13. In a fertilizer distributer, the combination of the body, the beater, the movable bottom for advancing the load to the beater, and means for simultaneously moving the beater away from the load and for elevating the movable bottom from one plane to another.

14. In a fertilizer distributer, the combination of the load-carrying body with vertical side walls, the movable bottom for carrying the load backward, the beater, and the 100 brackets supplemental to the aforesaid parts and supported directly by the ground wheels and supporting the beater and the bottom independently of the walls of the body.

15. In a fertilizer distributer, the combination of the body, the beater, the movable bottom for advancing the load to the beater, the through axle, the ground wheels mounted thereon, and the brackets hinge-connected to the axle for supporting both the 110 beater and one end of the movable bottom.

16. In a fertilizer distributer, the combination of the body, the means for supporting the load material and feeding it along the body, the axle, the ground wheels, and 115 the longitudinally swinging rotary beater supported upon the axle independently of the body and arranged to have its circles of rotation outside of the axle.

17. In a fertilizer distributer, the combination of the body, the means for supporting the load material and feeding it along the body, the axle, the wheels, and the beater mounted on the axle, and rotating entirely outside of the axle and adjustable longitudinally of the body.

18. In a fertilizer distributer, the combination of the body, the means for supporting the load material and feeding it along the body, and the beater supported on the 120

axle independently of the body and having its circles of rotation entirely outside thereof and movable toward and from the load material.

5 19. In a fertilizer distributer, the combination of the body, the means for supporting the load material and feeding it along the body, the axle, the wheels, the beater having its circles of rotation entirely outside 10 of the axle independently of the body, and the swinging carrier for the beater supported on the axle.

20. In a fertilizer distributer, the combination of the body, the means for supporting the load material and feeding it along the body, the axle, the wheels, the beater supported on the axle independently of the 15

body and arranged to have its circles of rotation entirely outside of the axle, and means for moving the beater from one position to another vertically. 20

21. In a fertilizer distributer, the combination of the body, the rear wheels, the axle, the means for supporting and feeding the material, and the beater arranged to have 25 its circles of rotation entirely outside of the axle and adapted to swing longitudinally across the vertical plane of the wheel axis.

In testimony whereof I affix my signature, in presence of two witnesses.

THEOPHILUS BROWN.

Corrections in Letters Patent No. 1,139,483.

It is hereby certified that in Letters Patent No. 1,139,483, granted May 18, 1915, upon the application of Theophilus Brown, of Moline, Illinois, for an improvement in "Manure-Spreaders," errors appear in the printed specification requiring correction as follows: Page 3, line 59, for the word "removing" read *moving*; page 4, line 10, strike out the words "independently of the body;" same page, line 12, after the word "axle" insert the words *independently of the body*; and that the said Letters Patent should be read with these corrections therein that the same may conform to the record of the case in the Patent Office.

Signed and sealed this 27th day of July, A. D., 1915.

[SEAL.]

R. F. WHITEHEAD,
Acting Commissioner of Patents.
